Application November 18, 1953, Serial No. 27,654

Term of patent 14 years

(Cl. D81—10)

To all whom it may concern:

Be it known that I, Arthur D. Altemiller, a citizen of the United States, residing at Afton, St. Louis County, State of Missouri, have invented a new, original, and ornamental Design for a Popcorn Warmer Casing, of which the following is a specification, reference being had to the accompanying drawing, forming a part thereof, in which:

Fig. 1 is a top plan view of a popcorn warmer casing, showing my new design;

Fig. 2 is a front elevational view thereof;

Fig. 3 is a side elevational view thereof; and
Fig. 4 is a rear elevational view thereof.

The other side of the popcorn warmer casing is identical with that shown in Fig. 3.

I claim:

The ornamental design for a popcorn warmer casing, substantially as shown and described.
